UNITED STATES PATENT OFFICE.

JOHN G. TARWATER, OF WARRENTON, NORTH CAROLINA.

VALVE-OPERATING MEANS.

Application filed August 29, 1923. Serial No. 659,999.

To all whom it may concern:

Be it known that I, JOHN G. TARWATER, a citizen of the United States, residing at Warrenton, in the county of Warren and 5 State of North Carolina, have invented a new and useful Valve-Operating Means, of which the following is a specification.

This invention relates to automobiles, and has special reference to an attachment for 10 operating the drain cocks of automobile radiators.

It is common in the construction of water cooled automobile engines to provide a radiator having at a suitable point at the bottom 15 a drain cock so that the water in the radiator and cooling system may be drained out whenever necessary. For instance, it is advisable in freezing weather to drain the automobile radiator whenever it is left to stand 20 for any length of time. This drain cock, by reason of being necessarily at a low point in the cooling system, is generally very inconvenient to reach, and it is frequently necessary for a person, in order to reach this 25 drain cock, to lie down on the ground or to reach in past the front wheels of an automobile. In either case one is apt to soil his clothes, and it is of course inconvenient otherwise.

30 The principal and most important object for the present invention is to provide an improved device for manipulating the drain cock from a point within the automobile body so that the driver of the machine may, 35 without any inconvenience, open and close the drain cock.

Another objection which exists with the 40 present arrangement of drain cocks is that they frequently become clogged with mud and dirt owing to their location close to the road, and thus even when open the water fails to flow out. As a result, it is frequently necessary to open the drain cock and then to clear the water passage with a wire or the 45 like, thus exposing the person performing the operation to being splashed with dirty water.

A second important object of the invention is to provide a housing for automobile 50 drain cocks which will prevent the accumulation of dirt and mud on the drain cock itself.

With the above and other objects in view 55 as will be hereinafter apparent, the invention consists in general of certain novel de-

tails of construction and combinations of parts hereinafter more fully described, illustrated in the accompanying drawings and specifically claimed.

In the accompanying drawings like characters of reference indicate like parts in the several views, and:

Fig. 1 is a side elevation, partly broken away, of a portion of an automobile showing the particular arrangement of the device.

Fig. 2 is a front view thereof.

Fig. 3 is a detail plan view of the operating mechanism.

Fig. 4 is a detail perspective view of the 70 housing employed.

Fig. 5 is a detail rear elevation of a drain cock especially arranged for use in this connection.

Fig. 6 is a detail perspective view of a 75 certain guide clip used herewith.

In the present embodiment of the invention, there is disclosed an automobile 10, having the usual hood 11 and radiator 12. Extending from this radiator at the bottom 80 is a circulating pipe 13, and a drain cock 14 is located at the lowermost point of this circulating pipe. This drain cock is of the ordinary plug valve type, but instead of being provided with a butterfly handle on the 85 plug, as with the ordinary construction, it is provided with an arm 15 which is normally vertically disposed and has at its free end an opening 16. The steering column of the automobile is shown at 17, and surrounding this steering column is a clip 18 having laterally extending ears 19 provided with confronting semi-tubular guide edges 21. The clip is held on the steering column by means of a clamp bolt 22. Slidably mounted between the guide edges 21 is a reach rod 23, which has its lower end pivotally connected to the arm 15, as by fork 24 provided with a suitable pin passing through the opening 16. This reach rod also passes through a suitable opening formed in the bearing plate 25 of the steering column, and has at its upper end an operating handle 26.

At 27 is a housing which is provided with laterally extending ears 28 so positioned that the ordinary bolts used in the construction of the automobile 10 may pass through these ears, and thus enable the housing to be secured in position beneath the drain cock 14. In the bottom of this housing, there is 110

provided an opening 29, and this opening is disposed out of alignment with the drain cock so that water from the drain cock will splash on the bottom of the housing, and thus have a tendency to remove any dirt or dust that may accumulate thereon.

It will now be obvious that the operator of the machine has convenient to his hand, means by which he may open the drain cock 10 14 whenever he desires to drain the cooling system, it being merely necessary to pull upon the rod for this purpose. Also it will be plain that the housing or guard 27 protects the drain cock from mud being thrown 15 against it, and thus prevents clogging of the water passage therein.

While the arm 15 has been shown in depending position, it is clear that it may also extend inwardly if desired without in any 20 way altering the construction.

There has thus been provided a simple and efficient device of the kind described and for the purpose specified.

It is obvious that minor changes may be 25 made in the form and construction of the invention without in any way departing from the material spirit thereof. It is not, therefore, desired to confine the invention to the exact form herein shown and described; but it is intended to include all such 30 as properly come within the scope claimed.

Having thus described the invention, what is claimed as new, is:

1. The combination with an automobile having a radiator provided with a drain cock and having a steering column; of a reach rod having one end connected to the drain cock and extending rearwardly alongside of said steering column, a support on said steering column wherethrough the 35 reach rod passes, an operating handle on the rear end of said reach rod, and a housing extending beneath said drain cock and having an escape opening therein out of alignment with the drain cock. 40

2. The combination with an automobile having a radiator provided with a drain cock and having a steering column; of an operating arm projecting from the drain cock in a normal vertical position, said arm 50 having an opening in its free end, a guide mounted on said steering column, a reach rod extending slidably through said guide and having its forward end provided with a fork, a pin passing through said fork and through said opening, a hand grip on the rear end of said reach rod, and a housing extending beneath said drain cock and having an escape opening therein out of alignment with the drain cock. 55

JOHN G. TARWATER.
